UNITED STATES PATENT OFFICE.

FRANK A. BAKULA, OF ST. LOUIS, MISSOURI, ASSIGNOR TO ALFRED VESTER SONS, INC., OF PROVIDENCE, RHODE ISLAND, A CORPORATION OF RHODE ISLAND.

DESIGN FOR A WALL PLATE FOR LIGHTING FIXTURE.

Application filed March 18, 1924. Serial No. 8,981. Term of patent 14 years.

To all whom it may concern:

Be it known that I, FRANK A. BAKULA, a citizen of the United States, residing at St. Louis, in the State of Missouri, have invented a new, original, and ornamental Design for a Wall Plate for Lighting Fixture, of which the following is a specification, reference being had to the accompanying drawing, forming part thereof.

Fig. 1 is a front elevation view, and Fig. 2 is a side elevation.

I claim:

The ornamental design for a wall plate for lighting fixture, as shown.

FRANK A. BAKULA.
